UNITED STATES PATENT OFFICE.

FRANK W. SCOTT, OF KIRKLAND, ILLINOIS.

SHEEP SHEARS.

Application filed January 21, 1927. Serial No. 162,423.

This invention relates to power-operated sheep shears, or other hand tools of a similar character, and has for its principal object the provision of a shear of an improved design and construction wherein the cutter may be properly and accurately adjusted in its tension relative to the comb so as to cut properly the full width of the swath and also minimize the wear of the cutter and comb, and result generally in a more smoothly and quietly operating tool, and one which will give far better and longer service than those heretofore available.

More specifically stated the present invention provides a vibrator member trunnioned in the frame of the tool for its vibratory or oscillatory movement, and a tension member carried thereby to move therewith as a unit, the tension member having a rocker mounting intermediate its ends on the vibrator member and bearing at its forward end against the cutter to press the same against the comb, the rearward end intersecting the trunnion axis of the vibrator member and having an adjustable set screw bearing against its under side at this point to adjust the pressure of the forward end downwardly on the cutter. The tension member is forked at its forward end so that the spread fingers thereof engage the cutter at separated points in the arc of its reciprocation and is, furthermore, capable of rocking laterally with respect to the vibrator member so as to accommodate the cutter accurately to the comb throughout its sweep. This, of course, makes for a smoothly operating tool and minimizes wear, and is far superior to the impractical and unworkmanlike design incorporated in tools heretofore where the arm actuating the cutter also served to apply tension thereto, in which case the design necessitated a wabbly mounting of the arm which caused excessive wearing of the cutter and comb and, of course, premature dullness of the teeth and generally unsatisfactory operation. The tension adjustment secured by the screw bearing against the rearward end of the tension member is also far superior to the tension adjustments used heretofore, since the screw in oscillating with the vibrator member and tension member has no tendency to loosen or tighten after the proper adjustment of tension has been made. In earlier designs of shears the adjustment usually provided involved an adjusting nut or the like which did not oscillate with the

vibrating part and the vibration always had a tendency to change the adjustment and it was, therefore, difficult to keep the proper tension on the cutter.

My invention presents these and other advantages over prior constructions as will appear more clearly in the following specification in which reference is made to the accompanying drawing wherein—

Figure 1 is a view partly in plan and partly in section of a power driven shear of the kind referred to incorporating the improvements of my invention. This view is taken approximately on the line 1—1 of Fig. 2;

Fig. 2 is a central vertical longitudinal section taken on the line 2—2 of Fig. 1; and Fig. 3 is a front end view.

The same reference numerals are applied to corresponding parts in the three views.

The sheep shear illustrated, in common with other shears of a similar type, comprises a frame 5 providing a handle portion 6 by which the tool is grasped for use, the latter being hollow and providing a bearing for the terminal driving element 7 driven in the usual manner by connection with a flexible drive shaft at the outer end of the handle, as is well known in this art. The element 7 terminates within the housing 8 in a crank portion 9 having a ball 10 swiveled on the crank pin thereof and arranged for operation in a ball race provided in the cross-head 11 whereby to produce vibratory movement of the actuator for the cutter 12 and reciprocate the same relative to the comb 13. The construction thus far generally described is common to many types of sheep shears available at the present time. The shear of the present invention, however, distinguishes from these earlier tools, as was stated above, by providing a cutter actuator of novel construction and one wherein the cutter may be properly and accurately tensioned and will always maintain its adjustment without being affected by the vibratory action of the cutter actuator. This novel actuator is indicated generally by the reference numeral 14 and will now be described in detail.

The cutter actuator comprises a vibrator member 15 and a tension member 16. The member 15 has the cross-head 11 formed preferably integral with the rearward end thereof and extends forwardly toward the cutter 12, the forward end being conformed

to provide a yoke 17 having a bearing opening 18 therein for the reception of the intermediate portion of the tension member 16. The vibrator member 15 has axially aligned trunnions 19 and 20 provided by the extremities of a tube 21 fitting through an opening 22 in the body of the vibrator member, the tube 21 having a driving fit in the opening 22 or being otherwise suitably fixed 10 in position therein as by swedging. The trunnions 19 and 20 are received in journal bearings 23 and 24 provided in a plug 25 and bushing 26 suitably threaded in openings in the walls of the housing 8. Ample bearing is, therefore, provided for the vibrator member and vibration and its accompanying wear will be reduced to a minimum. The end thrust of the trunnion 19 resulting from the tension placed upon the cutter 12, as will presently appear, is assumed by the ball end 27 of a set screw 28 threaded within the trunnion 19. The ball end 27 engages within a socket 29 provided therefor in the plug 25 and lubrication is afforded 25 for both the thrust bearing at 29 and the journal bearing at 23 through an oil opening 30. The latter communicates with an oil well 31 provided in the top of the plug 25, the well being furnished with oil through 30 an oiler opening 32 in a cap 33 threading on the plug 25, the opening being normally sealed by a ball closure 34 held in place by a coiled compression spring 35. The set screw 28 is preferably held against turning by a 35 pin 36 passed therethrough and received at its ends in openings 37 provided in the trunnion 19. When there has been a certain amount of wear at the thrust bearing 29 the set screw 28 may be adjusted to take up any 40 end play by engaging a screw driver in the slot 38 from the remote end of the tube 21, the pin 36 being, of course, removed to permit such adjustment and being replaced after the same is made.

45 The tension member 16 has a rocker mounting in the bearing opening 18, previously referred to, so as to have capacity for endwise and lateral rocking movement. The capacity for endwise rocking movement permits the application of pressure on the cutter 12 by the forward end of the tension member while the capacity for lateral rocking movement, as will appear shortly, permits the tension member to accommodate the cutter 12 to the comb 13 throughout the length of its sweep. The tension member 16 for the latter reason is forked at its outer end and has the spread fingers 40 thereof provided with pointed 50 ends 41 for reception in holes 42 provided in the prongs of the cutter 12. The cutter employed may have two, three or more prongs. The tension member thus engages the cutter at separated points in the arc of its reciprocation and, by reason of its

capacity for lateral rocking movement, accommodates the cutter to the comb throughout its sweep, which, of course, makes for smooth and easy operation of the tool. The rearward end of the tension member 16 intersects the fulcrum axis of the vibrator member and extends through an opening 43 provided in the wall of the trunnion 20. An adjustable set screw 44 threading within the trunnion has a ball end 45 to engage a complementary recess 46 provided in the under side of the tension member 16. Obviously the tightening of the set screw 44 forces the rearward end of the tension member 16 upwardly and rocks the same in its bearing 18 so that the forward end is forced downwardly and presses the cutter 12 against the comb 13, the pressure on the cutter being equalized by reason of the spread fingers 40. A coiled compression spring 47 acting between the inner end of the set screw 28 and the top of the tension member 16 at the rearward end of the latter serves to hold the tension member in close contact with the set screw 44 so that any tendency to rattle or chatter is entirely eliminated and very close and accurate adjustment of the tension on the cutter may be made. The spring also raises the front end of the tension member when the screw 44 is loosened to release the cutter 12 for replacing the cutter. A change in cutters can thus be made with little difficulty or loss of time.

The operation of the tool is believed to be apparent from the foregoing description, namely, that the tension member 16 always moves with the vibrator member 15 as a unit in the vibratory or oscillatory movement of the latter in operation. The adjustment as to tension secured by the set screw 44 may be accomplished with ease and facility to secure the finest graduation in tension desired and, by reason of the equalizing action of the forked end of the tension member, the action of the cutter will be smooth and even from end to end of its sweep and positively devoid of jerkiness, chattering, and vibration and the accompanying noise. The fact that the set screw 44 threads within the trunnion 20 and is, therefore, caused to oscillate with the vibrator member and tension member eliminates a very common difficulty met with in tools of the present character, namely, that of the tension changing by reason of the vibratory action. There is positively nothing which in any way could affect the adjustment after it is made. A further feature worthy of mention is that the present tensioning means obviates the necessity for parts projecting above the actuator, or below it, which parts in previous constructions were objectionable in that they made it difficult in shearing as, for example, about and between the horns. Furthermore, attention is called to the ample bearings provided for

the various parts and to the facility with which these parts may be kept oiled. This, of course, greatly improves the operating characteristics of the tool and makes for longer and better service. It is also obvious that the tool may be easily and quickly disassembled for inspection, cleaning or repairs or change in the adjustment of the set screw 28. It is a simple matter to unscrew the 10 plug 25 and bushing 26 whereupon the entire actuator unit may be withdrawn from the front end of the tool. In this connection note the cut away portion 48 at the front end of the housing 8. The trunnion part 19 is arranged to pass through this opening. The lower wall of the housing 8 is also preferably cut out, as indicated at 49, to facilitate the withdrawal of the actuator unit by allowing egress of the trunnion 20 through this 20 channel.

I claim:

1. In a shearing tool of the character described, comprising a frame by which the tool is grasped for use, a fixed cutter comb on said frame and a reciprocating cutter cooperating with said comb, an actuator for said reciprocating cutter comprising two members of which the first is fulcrumed in said frame for vibratory action to reciprocate the cutter, and the second extends forwardly therefrom for engaging the cutter, the first member having an opening for receiving and supporting the second member whereby the latter is free to 35 have endwise rocking movement to adjust its forward end in relation to the cutter so as to press the same toward the comb, and screw threading means mounted in the one member and engaging the other member 40 positively to adjust the forward end of the second member toward the comb, the said means moving with the actuator and being independent of the frame so as not to tend to change in adjustment.

2. In a shearing tool of the character described comprising a frame by which the tool is grasped for use, a fixed cutter comb on said frame and a reciprocating cutter cooperating therewith, means for actuating 50 said reciprocating cutter comprising a vibrator member fulcrumed in said frame for vibratory movement, and a tension member moving with the vibrator member and extending forwardly therefrom for engagement at 55 its forward end with the cutter, said last mentioned member being supported at one point on said vibrator member for rocking movement relative thereto, screw-threading means arranged when adjusted to rock the 60 tension member relative to the vibrator whereby positively to force the forward end thereof downwardly and press the cutter against the comb, and spring means acting in the opposite direction arranged in the 65 loosening of the last means to raise the for-

ward end of the tension member away from the comb.

3. A structure as set forth in claim 2 wherein the screwthreading means comprises an adjustable set screw threading in 70 a part oscillating with said vibrator member and tension member whereby said screw when adjusted also oscillates with the two members and thus has no tendency to change its adjustment. 75

4. A structure as set forth in claim 2 wherein the support for said tension member on said vibrator member permits both endwise rocking movement of said tension member and lateral rocking movement, the forward end of said tension member being forked and arranged to bear on the cutter at points spaced laterally with respect to said mounting so that the lateral rocking movement of said tension member accommodates the cutter to the comb throughout its sweep. 80

5. In a shearing tool of the character described comprising a frame by which the tool is grasped for use, a fixed cutter comb on 90 said frame and a reciprocating cutter cooperating therewith, means for actuating and tensioning said reciprocating cutter comprising a vibrator member having upper and lower coaxial trunnion parts received in bearings in said frame to permit oscillatory movement of said member, said vibrator member having a part extending forwardly toward the cutter and providing a yoke at its forward end, a tension member engaged intermediate its forward and rearward ends by said yoke whereby said tension member is arranged for endwise rocking movement, means at the forward end of said tension member for engaging the cutter to actuate 100 the same and press it against the comb, the rearward end of said tension member intersecting the trunnion axis of said vibrator member, a set screw threading at the lower trunnion part and hence free to move there- 105 with arranged when adjusted to urge the rearward end of said tension member upwardly to cause the forward end thereof to be urged downwardly to press the cutter against the comb, and means to provide an end thrust bearing for the upper trunnion part of said vibrator member whereby to 110 assume the thrust of said tension member. 115

6. A structure as set forth in claim 5 wherein the last mentioned means comprises a hollow plug member threading in an opening in said frame and providing a journal bearing therein for the trunnion of said vibrator member, a ball part acting between the end of said trunnion and said 120 plug to communicate the end thrust of the former to the latter, and a set screw adjustable in said trunnion behind the ball part to take up end play. 125

7. A structure as set forth in claim 5 130

wherein the yoke on the vibrator member provides a support for the tension member permitting both endwise and lateral rocking movement of the latter for the purposes described.

8. In a structure as set forth in claim 5, the provision of a compression spring disposed within the vibrator member and acting against the upper side of said tension member at the rearward end thereof whereby to hold the same downwardly against the set screw.

9. In a shearing tool of the character described comprising a frame having a part for holding the tool, a fixed cutter comb on said frame, and a reciprocating cutter cooperating therewith, a vibrator member fulcrumed in said frame for vibratory action, a tension member bearing at its forward end on top of the reciprocating cutter and mounted on said vibrator member for movement therewith in the operation of the latter, said tension member extending rearwardly from the cutter to intersect the fulcrum axis of the 25 vibrator member, a bearing on said vibrator member spaced from the fulcrum axis thereof wherein said tension member is mounted for lateral and endwise rocking movement so that the forward end of the latter may be 30 adjusted up and down and laterally with respect to the cutter properly to tension the latter relative to the comb and accommodate itself thereto, and means disposed on the fulcrum axis of the vibrator member to bear 35 against the tension member whereby to urge

the forward end of the latter downwardly to tension the cutter.

10. In a structure as set forth in claim 9 wherein the last mentioned means is positive in its action in communicating a given 40 amount of adjustment to the rearward end of said tension member, the provision of a spring acting in the reverse direction against said tension member arranged to yield to permit the aforesaid adjustment. 45

11. In a structure as set forth in claim 5 wherein the upper trunnion has a set screw adjustable therein serving as an end thrust bearing for said trunnion and arranged when adjusted to take up end play, a compression spring disposed in said trunnion bearing at one end against the inner end of the set screw and at the other end against the tension member at the rearward end of the latter whereby yieldingly to force the 55 latter downwardly toward the set screw in the lower trunnion.

12. A structure as set forth in claim 5 wherein the frame has cut-out portions permitting the entry and removal of the upper 60 and lower trunnions of the vibrator member, and wherein the bearings for said trunnions comprise plugs threading in openings provided in said frame intersected by the aforesaid cut-out portions, said plugs when 65 threaded in place serving to retain the vibrator member in the frame by its trunnions.

In witness of the foregoing I affix my signature.

FRANK W. SCOTT.
